TOY THEATER STAGE

Lawrence Wise, Bronx, N. Y., assignor to Playette Corporation, New York, N. Y., a corporation of New York

Application December 15, 1942, Serial No. 469,043

3 Claims. (Cl. 46—13)

My present invention relates to a play theater or toy which is realistically constructed, which may be shipped flat and which may readily be erected even by a child, and which, when in erected position, may easily be operated by an unskilled user.

In toys, particularly those which are generally regarded as educational or self-help toys, it is of the utmost importance that the construction be such that it may readily be operated by a child, with or without the assistance of an adult.

The difficulty with puppet theaters and the like which have previously been known, is that the manipulation of the figures or the changing of the scene from one scene to the next requires a complexity of movements and skill of such high quality to be beyond the ability of the ordinary child for whom the toy is intended.

Where an attempt has previously been made to arrive at simplicity, the net result was the production of an immobile or static toy, wherein a group of figures or dolls were each moved about at the whim of the child.

A primary object of the present invention is the formation of a play theater so constructed and arranged that various prepared stories or scenes may be enacted in predetermined sequential order, solely by operations performed by the child; and wherein a simple movement of a handle by the child will result in a complete change of the scene which is presented in the play theater.

At the same time, and in order to create an economical structure which may be manufactured by mass production methods from paper, cardboard or other fibrous material, the theater is made in collapsible form, and the sequential arrangement of the scenes for any particular story is presented in a bound form.

The theater member is also provided with means for supporting the bound book containing the sequential scenes, and with means which are readily operated by the child for successively presenting scenes or pages from the bound book to view on the theater stage.

Accordingly, a further object of my invention, is the provision of a play theater so arranged as to receive and hold a bound book, the pages of which may be successively presented to view on the stage of the play theater.

Another object of my invention is the arrangement of the bound book element of the play theater so that a simple manual movement of a lever from one side to another will be sufficient to present successive pages.

Still another object of my invention is the arrangement of the bound book containing sequentially arranged scenes in such manner that two stories or two sets of scenes may be presented on opposite sides of the pages of the book.

The manner by which all of these objects are accomplished and many other objects of the present invention will in part be apparent, and where not apparent, pointed out, in the following description and drawings in which:

Figure 1 is a view in perspective of my play theater with a book arranged therein to be presented to view.

Figure 2 is a cross-sectional view taken on line 15 2—2 of Figure 1 looking in the direction of the arrows.

Figure 3 is a cross-sectional view taken on line 20 3—3 of Figure 1 looking in the direction of the arrows showing the arrangement of the theater and its contents with the top of the theater closed.

Figure 4 is a plan view of the bound book containing the sequential arrangements of scenes which are successively to be presented to view.

Figure 5 is a plan view of a developed blank which is to form the play theater.

Figure 6 is a plan view of the developed blank which is to form the back-drop or stage defining portion of the theater.

Figure 7 is a developed view of the blank which is to form the floor of the stage of the play theater.

Figure 8 is a plan view of a bendable supporting strip for the operating mechanism which sequentially presents the pages of a book to view.

Referring first to Figure 5, I have here shown the developed blank 10 from which most of the theater structure is formed. This blank comprises a back wall section 11, a side wall section 12, a front wall section 13, another side wall section 14, a bottom wall section 15, and top wall sections 16, 17 and 18.

These wall sections are hingedly connected together along the bend lines 20, 21, 22, 23, 24, 25 and 26.

The top wall sections 16, 17 and 18 are separated from each other by the cuts 28 and 29 in order that sections 16 and 18, may, when the play theater is permanently set up, be permanently in position while the section 17 may from time to time be lifted in order to insert a new book in the manner hereinafter described.

Referring again to Figure 5, the right hand side of the back wall section 11 is provided with 55 a tab 35 which may be coated with any suitable

adhesive and, when the sections 11, 12, 13 and 14 are folded up into a tubular quadrilateral structure, the tab 35 is secured to the left-hand end of the section 14 in order to complete the tube. It will here be obvious that after the tube is thus formed it may nevertheless be collapsed owing to the fact that a bend line 36 is provided between the tab 35 and the back wall section 11 and owing to the fact that the other walls may bend about the fold lines 20, 21, and 22.

Consequently, in the collapsed position of the manufactured tube, the width of the tube is equal to that of the width of one side wall plus one front or back wall.

When it is desired to set up the play theater, then the tube formed by sections 11, 12 and 13 and 14 is opened up into quadrilateral formation, and the top and bottom tabs 37, 38, 39, 40, 41 and 42 of the respective walls 14, 13 and 12 are bent over at right angles to their walls along the respective fold lines 44, 45, 46, 47, 48 and 49.

The top wall section 16 is then bent downwardly around the fold line 24 so that the side edge 50 thereof overlies the top tab 39 and the front edge 51 thereof overlies one end of the top tab 38.

The tongues 53 and 54 now register respectively with the slots 55 and 56 and may be inserted therein in the manner shown in Figures 1 and 2 in order to hold the top wall section 16 in place.

Similarly, the top wall section 18 is bent down so that the edge 60 thereof overlies the top tab 37 and the edge 61 thereof overlies the left-hand end of the top front tab 38. The tongues 62 and 63 may then readily be inserted in slots 64 and 65. The bottom wall section 15 is then folded up so that the edge 70 thereof underlies the tab 42, the edge 71 thereof underlies the tab 41, and the edge 72 thereof underlies the tab 40. Tongues 73, 74, 75 and 76 may then be inserted in the slots 78, 79 and 80 to secure the bottom wall 15 in place.

Tongues 73, 74, 75 and 76 are shown as bayonet type members, the ends of which may be wider than the respective slots into which they are to enter, so that they may be sprung into the slots and held therein. This is necessary in the case of the bottom wall to prevent the same from falling out, although it is not absolutely essential where the play theater is to rest on a solid base and is not frequently to be moved.

Similar formations may be used for the tabs 53, 54, 63 and 62 should that be deemed desirable.

When the blank of Figure 5 has been assembled in the manner previously described, it then assumes the form shown in Figure 1. However, it is desirable that a back-drop be provided for the stage of the play theater; and that a floor also be provided therefor.

In order to insert the back-drop and the floor member, the flaps 16 and 18 as well as the flap 17 are first lifted. The back-drop member is shown in Figure 6 and comprises a back wall section 80, two rear side sections 81 and 82 and two front side sections 83 and 84, each separated from each other by the hinge lines 85, 86, 87 and 88. Side spacing tabs 89 and 90 may also be provided also separated from their respective walls 83 and 84 by the fold lines 92 and 93.

With the play theater now in the form shown in Figure 1, the flaps 16, 17, and 18 are lifted and the stage floor member 100 of Figure 7 is inserted in place. For this purpose, the tabs 101, 102 and 103 are bent downwardly around the fold lines 104, 105 and 106. The tabs 101, 102 and 103 may be cut out so that they will not

interfere with the tongues 73, 74, 75 and 76 of the bottom wall.

Since the floor 100 of the stage is substantially equal in its cross-section to the cross-section of the box when it is set up, the flaps 101, 102 and 103 form legs which support the floor of the stage. These legs bear against the bottom wall 15 when the floor of the stage is inserted. The floor of the stage may be inserted as has previously been described through the top of the theater and is supported when in place in the manner shown in Figure 1.

The back-drop member is then folded up into the form indicated in Figure 1, and slid down into place. Tabs 110 and 111 are provided which register with the slots 112 and 113 in the stage floor 100 to hold the back drop in place. The short tabs 90 and 89 of the back-drop serve to space the sides thereof from the side walls in an appropriate manner. The top wall flaps 16 and 18 are then closed.

As will be obvious, the front wall 13 is provided with an opening 120 through which a small portion 121 of the floor of the stage projects in order to give a finished appearance to the play theater. The opening 120 has a suitable shape in order to correspond to the appearance of a theater.

In order to complete the full assembly, the top flaps 16, 17 and 18 are raised, and the handle supporting flap 130 is folded into position.

As shown in Figures 1, 5 and 8, the handle supporting flap comprises a flexible strip 130 having a portion 131 permanently secured to the upper portion of the front wall above the opening 120 and separated by a hinged line 132 from a section 133 to which is pivotally secured in any suitable manner as by the pin 134, a handle 135.

As seen in Figure 1, one end of the handle 135, projects outwardly through the slot 136 in the top of the front wall 13.

During collapsed position, the strip 130 is folded flat against the inside surface of the front wall 13 and owing to the flexibility of the material from which the front wall 13 is made, and also owing to the thin construction of the handle 135, the handle may also assume a position substantially parallel to the front wall 13 with one end of the handle projecting through the slot 136 and the other end of the handle projecting on the opposite side thereof.

When the stage is arranged in quadrilateral form, with the stage floor and the back drop in position, then the strip 133 is folded down around the hinge line 132 and the end 140 thereof is folded down once more into the slots 142, 142 at the forward end of the backdrop as shown in Figures 2 and 6. The handle is now supported in horizontal position with one end projecting outside of the slots 136 in the manner shown in Figure 3 and one end projecting on the inside. This handle may now be used to operate the pages of the book to bring them into view in sequential order.

After the play theater is fully assembled as above pointed out, the side members of the top wall 16 and 18 are always left in position while the central member 17 may be raised or lowered about the hinge line 25. This central member 17 as may be seen from Figure 5 is slightly longer than the other members 16 and 18 so that it may project slightly beyond the front wall in order that it may readily be grasped and lifted.

A book which contains the story arranged sequentially in picture form is shown in Figure 4. This book 150 consists of a plurality of pages 151

bound together in any suitable manner, as for instance, by the spiral binding 152 and secured by said spiral binding to the flap 153.

As seen in Figure 3, the flap 153 may, when the center top member 17 of the top wall is lifted, be inserted in the slot 154 in the back wall, thus supporting the back end of the book; while the front of the book is then supported on the inner end of the handle member 135. The top member 17 may now be dropped back into place while the book is thus supported at both the front and back walls. The inner end 135 of the handle member is arranged so that it is slightly smaller than the successive notches 159 and 160 in the successive pages 151 of the book 150.

As may readily be seen, notch 159 extends in one direction, while notch 160 in the page immediately below extends in the opposite direction. The notch in the third page will coincide with the notch in the first page while the notch in the fourth page will coincide with the notch in the second page, and so on.

When the book is inserted in position, the handle preferably should extend straight into the stage theater, perpendicular to the front wall. In this case, it will register with none of the notches, and thus will not permit any of the pages to fall.

When the handle 135 is now rotated about its pin 134 so that the inner end thereof registers with notch 159, the first page will fall and come into view in the manner shown in Figures 1 and 3. The remaining pages of the book will be supported.

When the handle 135 is now turned so that its inner end registers with the notch 160, the second page will fall into view, while the remaining pages will be supported. Thus by successive movements of the handle 135 from one side to the other, successive pages will be brought into view.

As shown in Figure 6, the back wall 80 of the back-drop is cut out at 170 in order to provide access to the slot 154.

In appropriate constructions, it will be obvious that the tab 153 of the book may be slipped behind the back wall 80 over the top edge 171, and between the back wall 80 of the back-drop and the back wall 11, since this forms the full equivalent of the slot 154.

After the play theater has been set up in the manner previously described, the child may raise the flap 17, take up a book 150, insert the flap 153 thereof in the back slot 154, and rest the front thereof on the handle 135 and then close the top flap 17. His mother may then start to read a story to him from a prepared text which is illustrated by the book, and after describing an incident or a scene, may indicate to the child by a signal, such as by the word "curtain" that the handle is to be moved; whereupon the child operates the handle in the manner previously described to one side or the other to cause a page to drop. The page which drops will then have a scene on it depicting the incident described. As the mother or instructor reads further on in the text describing another scene or incident, at the conclusion thereof or during the scene, the reader will again indicate by a signal such as the word "curtain," that the handle is to be operated; whereupon the child on operating the handle will bring the next page or scene into view.

When all the pages of the book are thus exhausted, the book may be taken out and turned over and the reverse sides of the pages successively brought into view.

Preferably, in the construction of the device, the diagonal distance from the slot 154 to the fold lines 85 and 88 of the back drop will be about equal to the length of a page, so that the page will fall into view in the manner shown in Figures 1 and 3.

By this means, a simply operated, easily set up, educational toy may be provided by the use of which the child may cooperate in the telling and depicting of a story or in the presentation of other entertaining or informative material.

In the foregoing, I have described my invention in connection only with a specific embodiment thereof. Many variations in the construction and operation of the various devices herein disclosed, within the spirit of my invention, should now be obvious to those skilled in the art. Accordingly, I prefer to be bound not by the specific disclosures herein but only by the appended claims.

I claim:

1. A play theater stage comprising a back wall, side walls and a bottom wall; a front wall having an opening therein defining the front of the stage, a horizontal stage floor supported in said opening parallel to said bottom wall; flanges depending from said stage floor in surface to surface relation with said side walls and said back wall; the ends of said flanges resting on said bottom wall; and means for supporting the bound end of a book on the back wall of said play theater, and additional means on the front wall section above the opening thereof for releasably supporting the free ends of the leaves of said book; said first mentioned means comprising a slot in the back wall of the play theater, and a tongue member hingedly secured to the bound end of the book and insertable in said slot.

2. A collapsible play theater comprising a front wall member, an opening in said front wall defining the front of a stage; a slot in said front wall centrally located above said opening, a pivoted bar having one end extending through said slot on the outside of said front wall, and an end extending on the inside of said front wall; means for supporting said bar in said front wall, said means comprising a longitudinal member of sheet material having one section secured to said front wall above said slot and extending along the top of said front wall; said longitudinal member having a second section foldable substantially perpendicular to said first section, a pivot carried by said second section for pivotally supporting said bar; said longitudinal member having a third section foldable substantially perpendicular to said second section and engageable with a portion of the interior of said play theater to maintain said longitudinal member substantially in a channel shaped form.

3. A collapsible play theater comprising a front wall member, an opening in said front wall defining the front of a stage; a slot in said front wall centrally located above said opening, a pivoted bar having one end extending through said wall on the outside of said front wall, and an end extending on the inside of said front wall; means for supporting said bar in said front wall, said means comprising a longitudinal member of sheet material having one section secured to said front wall above said opening and extending along the top of said front wall; said longitudinal member having a second section foldable substantially perpendicular to said first section, a pivot carried by said second section for pivotally supporting said bar; said longitudinal member

having a third section foldable substantially perpendicular to said second section and engageable with a portion of the interior of said play theater to maintain said longitudinal member substantially in a channel shaped form; said bar, said longitudinal member, and said front wall member being formed of relatively thin sheet material whereby when all of the sections of the longitudu-

5 dinal member are folded into a plane parallel to that of the front wall; the manually graspable portion of said handle member may, nevertheless, extend through said slot parallel and adjacent to the outside of said front wall, and the interior of said portion of said handle may extend parallel to and adjacent the interior of the front wall.

LAWRENCE WISE.
